MULTI-CAMERA TV MONITOR PUSH-BUTTON CONTROL DEVICE

Walter G. Anders, Canton, Ohio, assignor to Diebold,
Incorporated, Canton, Ohio, a corporation of Ohio

Filed Oct. 9, 1967, Ser. No. 8,934

Term of patent 14 years

(Cl. D26—14)

Fig. 1

Fig. 5

Fig. 6

Fig. 2

Fig. 3

Fig. 4

FIGURE 1 is a perspective view of the multi-camera TV monitor push-button control device showing my new design;

FIG. 2 is a top plan view showing the top of the device;

FIG. 3 is a front view showing the front of the device;

FIG. 4 is a bottom plan view showing the bottom of the device;

FIG. 5 is a side elevational view showing the side illustrated at the right of FIG. 1; and

FIG. 6 is a rear elevational view of the device.

I claim:

The ornamental design for a multi-camera TV monitor push-button control device, as shown.
